UNITED STATES PATENT OFFICE.

EDWARD J. BAUR, OF ST. LOUIS, MISSOURI.

ASH-RECEPTACLE.

1,160,820.

Specification of Letters Patent.

Patented Nov. 16, 1915.

Application filed January 2, 1914. Serial No. 809,925.

To all whom it may concern:

Be it known that I, EDWARD J. BAUR, a citizen of the United States, residing at St. Louis, State of Missouri, have invented certain new and useful Improvements in Ash-
5 Receptacles; and I do declare the following to be a full, clear, and exact description of the invention, such as will enable others skilled in the art to which it appertains to

make and use the same.

This invention relates to improvements in ash receptacles and the primary object of the same is to provide a receptacle so constructed as to obviate the danger of any dust
15 from the ashes escaping.

A secondary object is to provide a simple, strong and efficient receptacle of the character described which will be well adapted to the above stated purpose.

20 With the above objects in view, the invention resides in certain novel features of construction and operation herein described and claimed and shown in the accompanying drawings wherein:

25 Figure 1 is a front elevation of my improved ash receptacle; Fig. 2 is a vertical section on the line 2—2 of Fig. 1; Fig. 3 is a vertical section taken at right angles to Fig. 2; and Fig. 4 is a horizontal section taken on
30 the line 4—4 of Fig. 1.

In the embodiment illustrated, my improved ash receptacle is shown in the form of a rectangular casing 1 closed at its upper end by a cover 2 which may be either fixed
35 or removable and having its lower end closed by a bottom 3 which, like the cover 2, may be either fixed or removable to adapt the receptacle to different uses.

30 Disposed within the casing 1 at a point intermediate its upper and lower ends, is a hopper 4 which as shown, comprises four inclined walls 5 secured to the walls of the casing 1 at their upper ends and having their lower ends terminating at a suitable point
45 to provide a discharge opening of the proper dimensions.

By the disposition of the hopper 4, I provide an upper compartment 6 which I will call the dust hood and a lower compartment
50 7 which I term the ash retaining chamber. By reference to the drawings, it will be seen that the dust compartment 6 is provided with a horizontal inlet opening 8 in which a horizontally hinged door 9 is adapted to
55 close, while the ash retaining compartment 7 is provided with a door opening 10 which

is normally closed by a vertically hinged door 11. I preferably provide both of the above mentioned doors with spring hinges 12 although it will be understood that independent springs or weights could be employed for holding them normally closed.

Located above each door opening in an inclined dust deflector 13 for a purpose to appear.

In the operation of the device, an ash can or bucket B is placed within the ash receiving compartment 7 and the door 11 is allowed to close through the action of its spring hinges 12. Ashes can then be taken direct from the furnace or stove by means of a shovel, the door 9 into the dust compartment may then be opened and the shovel inserted and given a half turn. This will discharge the ashes into the hopper 4 from which they will be directed into the can or bucket B in the ash receiving compartment. Any dust which may rise during this operation will be trapped in the upper end of the dust compartment 6 and when the shovel is removed the door 9 will be closed by its hinges 12 and no dust will be allowed to escape. If the above operation is repeated successively, a great deal of dust will have collected in the dust compartment 6 and in order to prevent it from flowing out of the inlet opening 8, when the door 9 is open, the upper deflector 13 is employed.

Although it is very advantageous to handle the ashes in the above described manner at night and remove the bucket B from the lower compartment in the morning when all dust is settled, it may be necessary at times to remove the bucket B before the dust has entirely settled. Considerable dust will have been trapped in the upper end of the lower compartment and in order to prevent this dust from flowing out the lower opening 10 when its door 11 is open, I also employ a deflector 13 over said lower opening.

In order that no dust may be allowed to escape from the ends of the opening 8, I provide the door 9 with arcuate shields 14 which are, as shown, in contact with the end walls of said opening.

By the above described construction, I provide a simple and strong article which is very efficient in operation and which will allow no dust whatever to escape if operated in the proper manner.

Although I have herein described my invention as being provided with the hopper

4 for directing ashes into the bucket B, it will be readily understood that if the bucket be of such size as to fit snugly within the lower end of the casing, the hopper 4 might 5 be easily dispensed with. I may so construct the bottom 3 of the casing that it may be entirely removed and the complete device placed over any receptacle adapted to receive ashes.

10 Although I have described my invention with considerable minuteness as to details, I do not wish to be limited to features of construction other than those amplified in the appended claim, neither do I wish to be limited to the use of the device in handling ashes since it will be clearly understood that it will operate to equal advantage in the handling of any substance from which dust is prone to rise.

15 20 What I claim as my invention:

The combination in an ash receptacle with a funnel-shaped hopper secured therein intermediate its ends, an outlet opening, a deflector plate and a hinged closure for the 25 same in one side of the receptacle below the

hopper, of a rectangular dust receiving chamber formed by the upper portion of said receptacle above the hopper, said receptacle having an elongated inlet opening extending transversely in one of its sides adjacent the top of the hopper, an outwardly swinging closure for said opening mounted on a horizontal axis above the same, and an angular deflector plate having its upper portion secured to the inner wall of the casing 30 above said inlet opening, and the lower portion thereof projecting inwardly and downwardly therefrom, whereby dust arising from ashes poured through the inlet to said receptacle is prevented from escaping there-through and is retained in the dust receiving chamber until it settles.

15 20 In testimony whereof I have hereunto set my hand in presence of two subscribing witnesses.

EDWARD J. BAUR.
